TARGET INFLATION DEVICE WITH TIMER CONTROL

TARGET INFLATION DEVICE

This invention relates to a device for inflating targets of the inflatable type, such as are used by the armed services for training in marksmanship, alertness and rapid response to changing combat situations.

In combat training, it has been found extremely useful to subject the trainees to simulated combat conditions, in which movable targets representing enemy soldiers, gun emplacements, tanks or other vehicles, appear suddenly within firing range, in order to test and improve the trainees' reaction time and the accuracy of their gunfire under conditions of stress. For optimum results, not only the time but also the place where the target will appear must be unpredictable by the trainees. Thus a training field having mechanically movable targets operable from predetermined locations cannot be reused for the same trainees and has only limited training value.

It is therefore among the objects of the present invention to provide a device for inflating targets of the inflatable type, which may be placed at any location in the training area and which is entirely self-contained, requiring no external wiring or other connections for remote control or energization.

Another object is that of providing such a device which is economical in construction, but foolproof in operation, and which is reusable an indefinite number of times, and sufficiently rugged to withstand rough handling and even dropping from a helicopter, for example, to permit rapid random placement in a training area.

In the drawing:

FIG. 1 is an end elevational view of an illustrative device embodying features of the invention;

FIG. 2 is a horizontal sectional view taken on the line 2-2 of FIG. 1; and

FIG. 3 is a side elevational view, at reduced scale, showing the device of FIGS. 1 and 2 following inflation of an inflatable target thereby.

The illustrative device shown in the drawing comprises a housing 10 formed to provide a pair of cylindrical chambers 12 for receiving a pair of compressed gas cylinders 14, for example the small carbon dioxide cartridges used in carbonated water dispensers. These cartridges 14 are axially slideable into and out of the chambers 12 and are held in position therein by removable screw caps 16 which seal the outer ends of the chambers 12 against the escape of gas.

The inner ends of the cartridges 14 bear against the ends of helical compression springs 18 whose opposite ends bear against hammers 20 which are supported for longitudinal sliding movement in the chambers 12, with their outer faces normally abutting shoulders at the inner ends of the chambers. The hammers 20 are provided at their inner faces with spikes 20a which are positioned in axial alignment with the seals at the inner ends of the cartridges 14, but which are normally held in spaced relation to the seals by the springs 18.

The portions of the chambers 12 between the cartridges 14 and hammers 20 communicate through a transverse passageway into a tubular nipple 26 which is mounted in the housing 10 and which, as shown in FIGS. 1 and 3, projects from its upper face in position for attaching thereto the mouth of an inflatable target 28.

The inner ends of the chambers 12 are connected to another transverse passageway 24 which also communicates with the nipple 26 and with a firing chamber 30 containing an explosive charge or squib 32, for example of black powder. Embedded in the squib 32 are a pair of wires 34 and 36 which extend through a third transverse passageway, which is sealed against the percussive force of the squib 32 by a sealing compound 40, and into a power cavity 41 closed by a plate 42 removably secured to the housing 10 by screws 43. The power cavity contains a battery 44, a switch 46 and an adjustable time delay element 48. The wire 34 is connected to the negative terminal or metal case of the battery 44, while the wire 36

is connected to its positive central terminal through the switch 46 and time delay element 48 in series. The contacts 46a and 46b of the switch 46 are spring urged toward conductive engagement but are normally held in separated, nonconductive relation by a safety pin 50 which is removably screwed into the housing 10 with its inner end 50a of insulating material interposed between the switch contacts 46a and 46b.

To actuate the device, the pin 50 is unscrewed and removed from the housing 10, allowing the switch contacts 46a and 46b to close. After the desired time delay, as determined by the adjustable time delay element 48, the voltage of the battery 44 appears across the conductors 34 and 36 within the squib 32, detonating the squib 32 and creating an explosive pressure which drives the hammers 20 outwardly against the resistance of the springs 18, causing the spikes 20a to perforate the seals at the inner ends of the cartridges 14. The gas within the cartridges 14 is thus allowed to expand, through the passageways 22 and 24 and nipple 26, into the inflatable target 28, rapidly inflating it.

As will be understood, these devices may be rapidly placed at random locations in a training area, for example by dropping them from a helicopter. After a desired time interval sufficient to allow trainees to move into the area, the devices will be actuated automatically to inflate the targets at random intervals, thus giving the trainees the realistic sensation of the sudden appearance of enemy units within their firing range.

Following such a training session, the devices may be retrieved and prepared for reuse by replacing the cartridges 14, the safety pin 50, and the squib 32. The battery 44 may also be checked and replaced if necessary.

The housing 10, being formed principally of a solid block, for example of metal, such as brass, is extremely rugged. The chambers and passageways may be formed therein by drilling or, for greater economy in large volume production, by casting. For ease of fabrication and service, each of the chambers and passageways terminates in an opening in one of the sides of the housing 10, with these openings being normally closed off by removable, gas-tight screw caps 52.

It will be apparent that various modifications may be made in the specific illustrative embodiment disclosed without departing from the principles of the invention. For example, the size and shape of the inflatable target and the likenesses printed thereon are readily changeable to simulate various types of hostile personnel or equipment. The number and size of the gas cylinders may also be changed. The electrical time delay device illustrated may be replaced by a fuse, for example. And the battery may be replaced by a condenser charged from an external power source.

I claim:

1. An inflation device for an inflatable target, comprising a housing, at least one chamber in said housing for receiving a compressed gas cylinder, a movable hammer at one end of said chamber for perforating the seal on said gas cartridge, an explosive charge for actuating said hammer, an electrical source in said housing, time delay means in said housing activated by said electrical source to detonate said explosive charge at a predetermined time interval after such activation, and actuate said hammer to perforate said seal, a nipple on said housing for engaging the mouth of an inflatable target, a passageway connecting said chamber with said nipple for conducting the expanding gas from said gas cartridge into said inflatable target.

2. An inflation device for an inflatable target, comprising a housing, at least one cylindrical chamber in said housing for slidably receiving a compressed gas cylinder inserted axially therein, a cap at the outer end of said chamber removably engaging said housing for sealing said chamber but permitting insertion and removal of said cylinder, a hammer mounted at the inner end of said chamber for sliding movement longitudinally of said chamber into perforating engagement with a seal at the inner end of said cylinder, a compression spring interposed between said cylinder and said hammer for holding them in normally separated relation, a nipple on said housing

for engaging the mouth of an inflatable target, a passageway connecting the inner end of said chamber with said nipple, a firing chamber in said housing communicating with said passageway, an explosive charge in said firing chamber, a battery in said housing, switch means in said housing electrically connected to said battery, time delay means in said housing connecting said battery through said switch means to said explosive charge to detonate said explosive charge a predetermined time after closure of said switch means and move said hammer against the resistance of said spring to perforate said seal and release the gas in said cylinder to inflate said target.

3. A device as described in claim 2 in which said switch

comprises a pair of switch contacts spring urged toward conducting engagement, with a firing pin removably engaging said housing and normally holding said contacts in spaced, non-conductive relation.

5. A device as described in claim 2 in which said housing is formed of a solid block recessed to form said cylindrical chamber, said firing chamber and said passageway.

5. A device as described in claim 4 in which said battery is contained in a cavity in said block closed by a removable plate.
